(57) **CLAIM**

The ornamental design for a computer display, as shown and described.

DESCRIPTION

FIG. 1 is a top plan view of a computer display showing our new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a cross-sectional view taken along the line of 7—7 as shown in FIG. 2 thereof, which omits the internal structure; and,

FIG. 8 is a perspective view of the top, front and right side thereof.
